New York

Application June 22, 1932, Serial No. 618,707,
and in Germany July 29, 1931

12 Claims. (Cl. 179—171)

Our invention relates to electronic valve systems and more particularly to electronic cascade amplifiers in which a direct or conductive coupling from the output electrode of one 5 valve to the input electrode of a subsequent valve is provided.

This type of amplifier is known as direct coupled amplifier or continuous current amplifier due to its use for amplifying very slow current variations for relay operation and the like. It has the further advantage of possessing a flat top frequency response curve comprising an extended band of frequencies, which makes 10 its application especially suited for purposes where increased fidelity of reproduction is of 15 primary importance such as for the amplification of sound and speech currents in public address systems, talking moving picture systems, and the like.

20 Direct coupled amplifiers are especially suited for amplifying television signals due to the extended signal frequency bands encountered in television transmission.

25 It is an object of our invention to provide a direct coupled electronic valve circuit of simple design and of increased efficiency and dependability in operation.

In direct coupled amplifier systems hereinbefore used and described in the prior art, an increased operating voltage is usually required dependent on the number of valves connected in cascade in case it is desired to use a common voltage supply source for operating all of 35 the amplifying valves.

Accordingly, it is another object of our invention to provide a circuit requiring a decreased operating voltage compared with systems used in the prior art.

40 A more specific object of our invention is to provide a direct coupled cascade system in which a self inductance coil may be used as a coupling means resulting in a simplified circuit arrangement and ease of operation.

45 These and further objects and aspects of our invention will become more apparent from the following detailed description taken with reference to the accompanying drawing, illustrating a few circuit arrangements in which 50 the invention has been embodied. We wish it to be understood, however, that the specific examples presented should be regarded as illustrative only of the underlying principle of the invention which, as will become obvious, is subject to many variations and modifications com-

ing within the broader scope of the invention, as expressed in the appended claims.

Figure 1 illustrates a known circuit presented for the sake of illustration and clearer understanding of the new circuit according to the 60 invention.

Figure 2 shows a novel circuit according to invention.

Figure 3 represents a modification of the circuit according to Figure 2.

Figure 4 relates to another modification of 65 the fundamental circuit of the invention according to Figure 2.

Similar reference characters identify similar parts throughout the different views of the 70 drawing.

Referring to Figure 1 of the drawing, this illustrates a known amplifying system with direct coupling, known also in the prior art as continuous current amplifier, since the output current of the last valve readily follows the slowest variations of the input potential applied to the first valve which latter may be a varying direct current obtained from a photoelectric device, thermo-couple, or the like.

The essential feature of this circuit consists 75 in a direct conductive coupling connection of the anode of the input valve V_1 to the grid of the output valve V_2 in such a manner that any coupling element except resistance r is dispensed with. In order to secure proper grid bias for the output valve for insuring efficient operation under the most favorable conditions, a balanced 80 circuit or bridge system is provided. One branch of the bridge is comprised of the resistors r_1 and r_2 and the other branch is comprised of the cathode-anode path of the valve V_1 on the one hand and the resistance r on the other hand.

The grid-cathode path of the valve V_2 forms 95 one of the diagonal branches of the bridge system, the remaining diagonal branch being formed by the power source indicated by the plus and minus signs in the drawing. In such a system, the grid bias voltage of V_2 will assume 100 negative values, if the ratio of the direct current resistance of V_1 to r becomes smaller than the ratio of r_1 to r_2 . For practical reasons, it was found necessary to operate direct current amplifiers from the alternating current house 105 networks in view of the high anode voltage required, which can easily be secured by a power pack including the usual transformers, rectifiers, and filter elements.

This makes it necessary to use an input tube 110

of the separate heater type. When using such a tube, it will require about one minute after the closing of a circuit switch until the cathode has become sufficiently heated for the anode current to begin to flow. At the instant of closing the circuit, therefore, the direct current resistance of V_1 is indefinite and will assume its operating value only after a certain period of time has elapsed.

From this it follows that immediately after the switching-on of the amplifier, a positive grid bias equal to the full anode voltage, will be applied to the grid of the valve V_2 , resulting in a high excess load being imposed upon the output valve during the starting period. As is obvious, this may injure or destroy the valve unless special precaution is taken to prevent overloading. One means to obtain this effect consists in the provision of a thermostatic switch closing the anode circuit only after the elapse of a few seconds. Such a switch has the disadvantage of being dependable in operation and it would not function properly immediately following the disconnection of the circuit.

Furthermore, it is known to provide a compensation circuit for applying a special grid bias during the starting period. This, however, complicates the circuit arrangement and entails an additional voltage drop, thus necessitating a further increase of the anode voltage and the cost of the apparatus. Also, the provision of a special auxiliary rectifying tube for producing starting grid bias has similar drawbacks.

As a further means for decreasing excess load of the output valve during the starting period, it has been suggested to increase the inner resistance of the battery eliminator supplying the amplifier sufficiently so that the excess load is kept within moderate limits. It is obvious that this method does not constitute a favorable solution of the problem.

In Figure 2, we have illustrated a novel circuit in accordance with the invention for overcoming the aforementioned disadvantages which besides assures increased efficiency of operation. According to the new circuit, the grid of the output valve V_2 is directly and conductively connected to the cathode of the input valve V_1 contrary to the usual connection to the anode, as 50 according to the prior art illustrated in Figure 1.

The drop of the signal voltage supplied by the input valve is produced by resistance r inserted in the cathode lead of V_1 . This circuit also constitutes a bridge circuit in principle. The resistance r and the direct current resistance of V_1 constitute one branch of the bridge and the resistances r_1 and r_2 , the latter being shunted by the cathode-anode path of V_2 forming the other branch of the bridge system. The 60 cathode-grid path of V_2 again forms the one diagonal branch of the system.

If no anode current is flowing through V_1 , the grid of V_2 will receive a negative bias equal to the voltage drop of r_1 , thus avoiding the danger 65 of excess load of V_2 during the starting. The grid bias voltage of V_2 will assume its proper operating value when the anode current through V_1 begins to flow, provided all the circuit elements are properly designed. The resistance r shunted by a capacity c in the cathode lead 70 of valve V_1 serves to provide the proper grid biasing potential for the valve input V_1 in a manner well known.

In a circuit just described a choke coil is substituted for the resistance r in accordance with

our invention, thus greatly simplifying both the design and operation of the amplifier. As is known, choke coils in contrast to transformers may be designed with sufficient impedance to enable their use for audio frequency amplification. As no further coupling elements in such a "direct choke coupling" are used, the amplifier will operate highly independent of frequency.

In Figure 3 we have illustrated an amplification system utilizing a choke coil as hereinbefore described. This circuit merely differs from Figure 2 in that choke coil d has been substituted for resistance r . A further simplification is obtained by omitting the resistance r_2 , in which case the value of resistance r_1 has to be increased. Thus, one arm of the bridge system is comprised by the cathode-anode path of V_2 in place of the combination of cathode-anode path with resistance r_2 connected in parallel thereto. This, as will be understood, makes it necessary to readjust resistance r_1 to restore proper balance of the system.

It is obvious that the resistance r_2 according to Figures 2 and 4 may also be dispensed with, with r_1 properly modified as pointed out. It is understood that both a resistance r and choke coil d in combination may be provided in the cathode lead of V_2 , thus combining Figures 2 and 3. The resistance r_2 which, together with r_1 forms a separate direct current circuit from the positive pole of the anode potential source over the cathode of V_2 to the negative pole of the source, in some cases has the effect of stabilizing the cathode potential of V_2 , thus insuring increased balance of the circuit.

The resistance r_1 has to be chosen in such a way that its voltage drop will secure proper operating voltage bias for valve V_2 . We have also shown in this figure a grid bias resistor w shunted by capacity c for securing proper operating bias of the grid of the input valve V_1 in a manner similar as described in Figure 2. One of the main advantages of the choke coil coupling, as illustrated, resides in the fact of a considerable decrease of the anode voltage required, as 105 compared with the resistance coupling illustrated in Figure 2.

Figure 4 shows a circuit in accordance with the invention similar to Figure 3 for use with direct current heater type valves in which, as is known, the valves are operated in series directly from a direct current supply system. In this case resistances r_1 and r_2 are connected in series with the cathode heater circuit as illustrated. Otherwise, the circuit is identical to the 110 circuit shown in Figure 3.

It is understood that the circuit as described may be modified in many ways without departing from the spirit of the invention. This, for instance, a common bulb may be used enclosing the electrode elements of both valves V_1 and V_2 with the cathode of V_1 directly connected to the grid of V_2 inside the common evacuated vessel, as is known in multiple tubes.

What we claim is:

1. In an electrical system, a first discharge valve; a second discharge valve, said valves having cathode, anode, and control electrodes; a source of energy; a direct conductive coupling connection from the cathode of said first valve to the control electrode of said second valve; means including circuit connections for connecting the anode circuits of said valves in parallel across said source; and a choke coil inserted in the cathode lead of said first valve.

2. In an electrical system, a first thermionic valve; a second thermionic valve, said valves having cathode grid and anode electrodes; a source of anode potential; a direct conductive coupling connection from the cathode of said first valve to the grid of said second valve; means including circuit connections for connecting the anode circuits of said valves in parallel across said source; and a resistance and a choke coil in series inserted in the cathode lead of said first valve. 80
3. In an electric system, a first thermionic valve; a second thermionic valve, said valves having cathode grid and anode electrodes; a source of anode potential supply; a direct conductive coupling connection from the cathode of said first valve to the grid of said second valve; means including circuit connections for connecting the anode of circuits of said valves in parallel across said source; impedance means inserted in the cathode leads of said valves comprising a choke coil in the cathode lead of said first valve for maintaining predetermined operating potentials of said electrodes and for producing coupling potential for said second valve. 85
4. In a system as described in claim 3, a resistance shunted by a bypass condenser in the cathode lead of said first valve for producing grid bias potential for said first valve. 90
5. In a system as described in claim 3, at least one further direct current circuit extending from the positive pole of said source over the cathode of said second valve, to the negative pole of said source. 95
6. In an electrical system, a first thermionic valve; a second thermionic valve, said valves having cathode anode and control electrodes; a source of anode potential supply; means for directly and conductively connecting the cathode of said first valve to the control electrode of said second valve; means including circuit connection from the anode of each of said valves to the positive terminal of said source; 100
